UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

DUPLICATING APPARATUS.

No. 809,287.

Specification of Letters Patent.

Patented Jan. 9, 1906.

Application filed February 4, 1905. Serial No. 244,138.

To all whom it may concern:

Be it known that I, ALBERT B. DICK, a citizen of the United States, residing at Lake Forest, in the county of Lake and State of Illinois, have invented a certain new and useful Improvement in Duplicating Apparatus, (Case A,) of which the following is a specification.

The invention is designed particularly for use in the duplication of autographic and type-written matter by means of a stencil mounted upon a drum. The object is to provide a simple, compact, and durable apparatus efficient and reliable in operation.

In carrying out the invention in the preferred form, which will be hereinafter described, I employ a drum upon the surface whereof the stencil-sheet is secured. Underlying and coacting with this drum is a pressure-roller spring-pressed toward the drum, but provided with means whereby the same may be withdrawn therefrom. Means are also provided whereby the pressure-roller is permitted to assume operative position (exerting pressure against the stencil-covered portion of the drum) during a certain portion of the movement of the latter, and whereby such roller will be thrown to inoperative position during the remainder of the movement of the drum, such means including a lock, operated, preferably, by the drum, to secure the pressure-roller temporarily in such inoperative position, but to release the same to permit its operative position when needed for the printing operation.

In the drawings, Figure 1 is a central longitudinal section of a duplicating machine embodying my improvement, illustrating the locking device above referred to in operative position and after the printing movement of the drum. Fig. 2 a detail view illustrating the locking device in inoperative position just before the printing movement of the drum; and Fig. 3 is a section on the line 3 3, certain parts being broken away to benefit the explanation.

Referring to these drawings, in which similar letters denote corresponding parts, it will be seen that the frame comprises, mainly, the two side plates A A', provided with upwardly-extending brackets a, in which are journaled the stub-shafts supporting the stencil-carrying drum. Said drum comprises two heads B B', and these are here shown as connected by two bars b.

b' designates the stencil-carrier of foraminated material, the ends thereof terminating at the cross-bars b. The stencil-carrier is preferably provided with a detachable ink-pad b², over which is secured the stencil-sheet b³. 60

C designates a shelf-plate extending from one to the other of the drumheads and provided with angular upturned ends c, whereby the same is secured (by riveting or other means) to such heads. 65

D designates a locking-plate overlying the shelf-plate C and here shown as secured by means of the angular downturned ends d to the angular upturned ends c of said shelf-plate. 70

E designates a stop-plate, here shown as provided with angular upturned ends e, whereby the same is secured to the drum-heads B B'. If desired, instead of mounting said plate E rigidly as here shown the same may be hinged, 75 so as to lie close to the plate D after the stencil-sheet has been placed in position. This may be accomplished by omitting the rivet at each end of the plate nearest to the forward edge of the stencil-carrier or in any other suitable manner. Projecting rearwardly from said stop-plate are angular inturned stops e'. 80

The stencil-sheet b³ may comprise either a waxed sheet alone or such a sheet combined 85 with another sheet or other sheets—as, for instance, a backing-sheet or a type-protecting sheet, or both. To secure such a stencil-sheet to the drum above described, it is necessary only to fold the forward end thereof upon itself, as illustrated in Fig. 1, and then to pass such forward end, the folded edge in advance, between the shelf-plate C and locking-plate D. The stops e' limit the degree of movement in this direction. If then the stencil-sheet be again drawn forwardly, the fold b⁴ 90

thereof will spring upwardly on the outer side of said locking-plate D and between the same and the stop-plate E, thereby properly positioning the sheet and securing the forward end thereof to the drum. The sheet may now be passed around the periphery of the drum upon the stencil-carrier b' and the rearward end thereof secured in any suitable manner—as, for instance, by means of the bail b⁵. 95

F designates a stencil-protecting plate, (best seen in Fig. 3,) the function whereof is to protect the stencil-sheet on the pick-up line—i.e., the point at which contact is made with the pressure-roller hereinafter to be described. 100 105 110

Said plate is preferably of thin metal, its forward edge coacting with screws f , secured to the drumheads or to the stencil-carrier thereon, its rearward edge being secured in position by means of latches f' , pivoted at f'' upon the stop-plate E. As will readily be seen, in order to remove the plate from the position in which it is shown in Fig. 3 it is only necessary to throw the latches f' to inoperative position and to lift the plate backwardly and upwardly to free the same from the screws f .

G G designate wings, here shown as secured to and extending inwardly from the inner faces of the drumheads B B'. The function of these wings is to aid in maintaining the impression-sheets level as against the tendency of either the lateral or longitudinal edges thereof (or both) to curl. Said wings assist materially in permitting the sheets to be passed to the paper-stop, presently to be described, and by which such sheets are properly positioned in advance of the printing operation.

The paper stopping and stripping mechanism is here shown as comprising a rock-bar H, journaled in the side members A A' of the frame and provided with forwardly-projecting paper stopping and stripping fingers h. Said rock-bar and fingers are operated by means of the rocking lever h', pivoted at h'' and provided with sheave h'', lying in the path of movement of a cam h⁴, secured to or formed integral with the drumhead B'.

I designates the pressure-roller, here shown as journaled at its ends in arms i, hinged at i' to the inner faces of the side members A A' of the frame. The free ends of said arms, with which coact coil-springs i⁵, are downturned at i'' and curved for coaction with cams i³, mounted upon rock-shaft i⁴, journaled also in the side members of the frame and provided outside such frame with the finger-piece i⁶. As will be seen, the operation of said finger-piece in one direction and consequent operation of the cams i³ will depress the arms i, and therefore the pressure-roller I, throwing the same out of operative relation to the stencil-carrying drum.

J J designate sheaves carried by the hinged arms i, one of these lying in the path of movement of the cam h⁴ on the drumhead B' and the other lying in the path of movement of a similar cam h⁵, secured to or formed integral with the other drumhead B. As will be seen, whenever the drum is turned to the point where said cams h⁴ and h⁵ are brought into coaction with the sheaves J the latter are depressed, thereby effecting also the depression of the pressure-roller I to inoperative position out of contact with the drum.

L L designate locking-levers, each of which is pivoted at l to the exterior of a hinged supporting-arm i and between such arm and the inner surface of the side plates A A' of the frame. Each lever extends downward and

forward from such pivotal point and terminates in a curved toe l', adapted to coact with the rock-shaft i⁴ by passing under the same, as shown in Fig. 1, when the roller I is depressed. Each lever also extends upwardly 70 from such pivotal point, as shown at l'', into the path of travel of a lock-operating stop or lug l³, formed on the external face of one of the drumheads.

In the present instance a stencil-carrying 75 drum has been shown which is of the oscillating type rather than of the rotary type—i. e., the movement thereof is not a continuous rotary movement, but in one direction to a point of arrest and then in reverse direction to a 80 similar point. The degree of movement of said drum may be determined by the coaction between the stops l³ and the extensions l² of the locks L, and such coaction operates, additionally, to lock the pressure-roller I out of 85 engagement with the periphery of the drum and to release the same for coaction with the stencil-covered portion thereof.

In operation the pressure-roller-carrying arms are freed from the restraint of the cams 90 i³. They are held downward, however, by the coaction of the cams h⁴ h⁵ with the sheaves J, thereby maintaining an open space between the periphery of the pressure-roller I and the drum. One of the pile of impression-sheets 95 laid upon the feed-board M is then fed forward between the guides m until its forward edge makes contact with the paper-stop. The drum is now turned in the direction indicated by the arrow, Fig. 2, and the cams h⁴ h⁵ pass 100 out of coaction with the sheaves J just in advance of the moment of coaction between the stencil-sheet and the pressure-roller. The latter is thereupon permitted to rise, so as to exert upward pressure upon the impression-sheet, thereby assuring firm contact of the latter with the stencil-covered periphery of the drum. This contact is maintained during the entire period of coaction of the drum and pressure-roller and until the cams h⁴ h⁵ again 105 come into coaction with the sheaves J, this signalizing the passage of the end of the stencil-sheet. At this point said cams again depress the pressure-roller I, and immediately thereafter (see Fig. 1) the lock-operating stops 110 or lugs l³ make contact with the extensions l² of the locks L, thereby rocking said locks upon their pivotal points l and bringing the curved toes l' thereof under the rock-shaft i⁴. This locks the pressure-roller in its lowermost position (and out of contact with the periphery of the drum) and maintains the same inoperative until the drum has again been returned in the opposite direction to the starting-point, whereupon contact of the stops or 115 studs l³ with the extensions l² (on the opposite side of the latter) will again rock the locks L and free the same from contact with the rock-shaft i⁴, whereupon the operation may be 120 repeated as before. It will of course be un- 125 130

derstood that as the stencil-covered portion of the periphery of the drum coacts with the pressure-roller the sheet is imprinted upon and fed outward from the machine, the paper stops and strippers being depressed to permit this at the moment when the forward end h^6 of the cam h^4 passes out of engagement with the sheave h^3 upon the rocking lever h' :

Having now described my invention, what I claim as new therein, and desire to secure by Letters Patent, is as follows:

1. In duplicating apparatus, the combination with a movable drum and an underlying pressure-roller, of means carried by said drum for flattening an impression-sheet in advance of the passage of the same between said drum and roller, substantially as set forth.

2. In duplicating apparatus, the combination with a movable drum and an underlying pressure-roller, of members mounted within the drum, at that point not covered by the stencil-sheet thereon, for coacting with an impression-sheet in advance of the passage of the same between said drum and roller, substantially as set forth.

3. In duplicating apparatus, the combination with a movable drum and an underlying pressure-roller, of means for passing an impression-sheet between said drum and roller and wings carried by said drum and extending adjacent to the path of such impression-sheet, substantially as set forth.

4. In duplicating apparatus, the combination with a movable drum comprising heads and a stencil-carrier, of wings extending inwardly from the inner faces of said drum-heads and adapted to coact with a sheet in advance of the passage thereof between said drum and roller, substantially as set forth.

5. In duplicating apparatus, the combination with a movable drum, of an underlying pressure-roller movable to operative and inoperative positions relatively to said drum, a lock positively coacting with said roller and means operated by said drum for actuating said lock to hold said roller in inoperative position, substantially as set forth.

6. In duplicating apparatus, the combination with a movable drum and an underlying pressure-roller movable to operative and inoperative relation to said drum, of means carried by the drum for moving said roller to inoperative position, and a lock operated by said drum for maintaining said roller in such position, substantially as set forth.

7. In duplicating apparatus, the combination with a drum and an underlying pressure-roller mounted on swinging arms and movable to operative and inoperative relation to said drum, of a lock for maintaining said pressure-

roller in inoperative position said lock including a lever mounted upon one of said arms, and means carried by said drum for moving said lever to locking and unlocking positions, substantially as set forth.

65

8. In duplicating apparatus, the combination with a movable drum and an underlying pressure-roller mounted upon hinged arms, of a cam carried by said drum and operating to throw said pressure-roller to inoperative position, a locking device for said pressure-roller, and means carried by said drum for operating said locking device, substantially as set forth.

70

9. In duplicating apparatus, the combination with a movable drum, of an underlying pressure-roller movable to operative and inoperative relation to said drum, means carried by said drum for moving said roller to inoperative position, and a lock for said pressure-roller having a member projecting into the line of travel of a projection upon said drum, substantially as set forth.

80

10. In duplicating apparatus, the combination with a movable drum, of an underlying pressure-roller mounted in hinged arms spring-pressed toward said drum, mechanism intermediate of said roller and drum for depressing the former, locking-levers carried by said hinged arms and adapted to lock said pressure-roller in inoperative position, and means carried by said drum for operating said levers, substantially as set forth.

85

11. In duplicating apparatus, the combination with a drum and a stencil and an attaching device carried thereby, of a stencil-protecting plate detachably secured to said drum independently of said device, said plate coacting with said stencil, substantially as set forth.

95

12. In duplicating apparatus, the combination with a drum and a stencil-attaching device carried thereby, of a detachable stencil-protecting plate independent of said device, and means carried by said drum and coacting with said plate at either edge thereof to maintain said plate in position, substantially as set forth.

100

13. In duplicating apparatus, the combination with a drum and a stencil-attaching device carried thereby, of a detachable stencil-protecting plate independent of said device, and latches carried by said drum for securing said plate in position, substantially as set forth.

110

This specification signed and witnessed this 30th day of January, 1905.
